J. B. ROBINSON.
INSTRUMENT FOR ASCERTAINING THE POINT OF RECALESCENCE OF STEEL.
APPLICATION FILED JAN. 16, 1919.

1,310,443.

Patented July 22, 1919

UNITED STATES PATENT OFFICE.

JOSEPH B. ROBINSON, OF ROCHESTER, NEW YORK, ASSIGNOR OF ONE-HALF TO CARL M. WEBER, OF ROCHESTER, NEW YORK.

INSTRUMENT FOR ASCERTAINING THE POINT OF RECALESCENCE OF STEEL.

1,310,443.

Specification of Letters Patent. Patented July 22, 1919.

Application filed January 16, 1919. Serial No. 271,535.

To all whom it may concern:

Be it known that I, JOSEPH B. ROBINSON, a citizen of the United States, and resident of Rochester, in the county of Monroe and 5 State of New York, have invented certain new and useful Improvements in Instruments for Ascertaining the Point of Recalescence of Steel, of which the following is a specification.

10 The present invention relates to an instrument for ascertaining the point of recalescence of steel and more particularly to the type having a magnet mounted upon a non-magnetic support, the magnet being 15 presented to the steel while the latter is in a heated state to determine whether the point of recalescence has been reached.

An object of this invention is to provide 20 in connection with the magnet an abutment which will permit the movement of the magnet on its support should the point of recalescence not be reached, but will prevent the movement of the magnet should the point of recalescence be reached, the magnet normally lying in coöperation with the abutment.

To this and other ends, the invention consists of certain arrangements of parts which 30 will be hereinafter described, the novel features being pointed out in the appended claims.

In the drawings:

Figure 1 is a side view of the instrument showing the magnet in coöperation with the 35 abutment;

Fig. 2 is a similar view partially in section showing the magnet moving away from the abutment under the action of the steel which has not reached the point of recalescence;

Fig. 3 is a transverse enlarged section on the line 3—3, Fig. 1;

Fig. 4 is a view on a reduced scale showing the position of the magnet when the latter 45 engages steel which has reached the point of recalescence; and

Fig. 5 is a detail view of the magnet showing the brass bearing.

Referring more particularly to the drawings, 50 1 indicates a supporting member which, in this instance, comprises a tubular bar made of brass or other suitable non-magnetic material, its tubular form being to prevent its becoming heated throughout its

length. Preferably secured at one end of 55 the bar is a strap or saddle 2 substantially U shape in form and having its arms receiving the bar 1 between them. Bolts 3 may secure the strap to the bar and the bar may be cut away at 4 on opposite sides to receive 60 the arms of the strap. The free ends of the strap may carry inwardly projecting pintles 5 on which the magnet 6 is mounted to turn, the magnet in this instance having between 65 its ends a transversely extending bearing piece 7 formed of brass or a non-magnetic material and having its ends formed with sockets 8 into which the pintles 5 project.

In this instance the magnet 6 is elongated and the pivot is arranged slightly to one side 70 of the center so that the weighted end tends to move into coöperation with an abutment 9 preferably formed by turning inwardly, a portion of an arm 10 extending from the support 1 to one side of the magnet, said 75 arm also being formed of non-magnetic material such as brass.

In the use of the instrument, the latter is introduced through the door 11 of the furnace to engage with the steel 12, its outer or 80 lighter end being pressed against the steel, thus holding the weighted end firmly in engagement with the abutment 9. Should the steel not have reached the point of recalescence, the magnet will be held by the steel 85 when the support is withdrawn and the weighted end of the magnet will be carried away from the abutment 9 thus indicating to the user that the point of recalescence has not been reached. Should the point of recalescence have been reached, the magnet will 90 not be affected by the steel, but will be pressed firmly against the abutment 9.

It is apparent that the invention is not limited to the construction herein shown. I 95 believe myself to be the first to provide a magnet which lies in engagement with a fixed abutment and which when pressed to the steel, if the point of recalescence has been reached, will be moved away from the abutment 100 to indicate to the user the condition of the steel, the magnet automatically returning to its coöperation with the abutment after the steel is disengaged, and the abutment serving to prevent any movement of the magnet when the latter is pressed against the steel after the point of recalescence has been reached.

What I claim as my invention and desire to secure by Letters Patent is:—

1. An instrument of the class described comprising a support, a magnet movably mounted thereon, and an abutment with which said magnet coöperates and from which it moves under the action of steel which has not reached the point of recalcitrance.
- 10 2. An instrument of the class described comprising a support, an abutment thereon, and a movably mounted magnet having a normal tendency to move toward the abutment and to be moved away from the abutment by steel which has not reached the point of recalcitrance.
- 15 3. An instrument of the class described comprising a support, an abutment thereon, and a pivotally mounted magnet having a normal tendency to lie in coöperation with

the abutment, and adapted to be moved away from said abutment by steel which has not reached the point of recalcitrance.

4. An instrument of the class described comprising a support, an abutment thereon, and a pivotally mounted magnet having a portion on one side of its pivot heavier than on the other side to hold said magnet into coöperation with the abutment from which said magnet is moved by steel which has not reached the point of recalcitrance.

5. An instrument of the class described, comprising a tubular support, arms depending from said support, a magnet pivoted between the arms and having a greater weight on the inner arm thereof than the outer arm, and an abutment against which the magnet is held by the heavier arm of the magnet.

JOSEPH B. ROBINSON
